BEAM DRIVE

Max E. Ebert, Palisades Park, N. J., assignor to Alfred Hofmann & Co., West New York, N. J., a corporation

Application January 26, 1953, Serial No. 333,260

8 Claims. (Cl. 66—86)

This invention relates to beam drives for knitting machines of the warp or tricot type.

The progressive increase in the operating speeds of the modern warp or tricot knitting machines, as well as the greater weight of the beams of such improved machines, has made mandatory, the use of a positive type drive for the let off of the beam.

In known beam drives of the positive type, the warp threads or yarns are fed continuously to the knitting instrumentalities and without any interruption during the knitting cycles. It follows, that a continuous, uninterrupted feed of the threads, limits the possibilities of variations in stitch construction of the fabric being formed. A number of stitch constructions are based on the use of floating or blind stitches. To achieve such constructions, the threads are passed through the guide bars of the machine without the formation of loops. This is only possible if the feed of the warp threads is temporarily halted. Accordingly, these special stitch constructions cannot be formed on conventional machines having a continuous beam drive.

Blind or floating stitches are formed when one warp is floating and other warps are knitting, thereby accumulating fabric which is pulled together by the floating threads. In this manner, a variety of fabrics may be formed which show pleated, buckled and other three dimensional novelty effects.

In forming these novelty fabrics, it is understood that during that number of the knitting cycles when the warp threads float to form the blind stitches, there is no demand for threads from the beam and accordingly, the thread feed from the beam must be temporarily suspended. For some stitch constructions of this type, the floating period may extend for as many as 40 knitting cycles.

Accordingly, an object of this invention is to provide a positively driven beam let off, wherein the thread feed may be discontinued completely for a predetermined number of knitting cycles, thereby allowing the formation of a predetermined number of blind stitches in accordance with the desired fabric stitch construction.

Another object of this invention is to provide a positive beam drive, wherein the pattern determining means of the knitting machine, controls the operation of means for halting the beam drive for a predetermined number of knitting cycles.

A further object of this invention is to provide in a beam drive of the character described, means for automatically adjusting the beam drive as the beam diameter varies, in order to maintain the linear speed of the beam let off at a substantially constant speed.

Yet another object of this invention is to provide in a beam drive of the character described, driving means having intermittent actuation, the intervals of actuation being so small as to provide substantially continuous rotation of the beam.

Yet a further object of this invention is to provide a beam drive having substantially continuous actuation,

2

together with means for micrometer adjustment of the actuating means whereby to vary the quality characteristics of the knitted fabric.

Still another object of this invention is to provide a beam drive which is of rugged construction yet is readily adjusted to insure precision operation, which is easily manufactured and installed, which can be economically serviced and which is practical and adaptable in use.

Other objects of this invention will in part be obvious and in part hereinafter pointed out.

In the drawing:

Fig. 1 is a diagrammatic representation of a beam drive embodying the invention;

Fig. 2 is an elevational view showing the ratchet portion of the drive; and

Fig. 3 is an elevational view showing the micrometer adjustment portion of the drive.

The beam drive of the instant invention comprises essentially, positive means for rotating the beam such as a ratchet arrangement or other suitable mechanical means interconnecting the beam drive shaft and a constant speed power shaft such as the cam shaft of the machine, together with means for suspending the operation of the connecting means for a predetermined number of knitting cycles, thus halting the rotation of the beam; means for regulating the speed of the beam drive to compensate for the decrease in beam diameter; and means for regulating the operation of the beam drive with micrometer precision.

Referring in detail to the drawing, 10 designates a beam drive embodying the invention. The same comprises a beam 11, from which threads or yarns, not shown, are let off and supplied to the knitting instrumentalities, not shown of the knitting machine with which the beam 11 is associated. A worm wheel 12 is fixed to the beam shaft 13 and a worm 14 meshes with said worm wheel. The worm 14 is fixed to a beam drive shaft 15 which is mounted for rotation in an upper bearing 16, an intermediate bearing 17 and the horizontal arm of a lower bearing 18 having a right angle form.

A bevel gear 19 on the lower end of shaft 15 meshes with a bevel gear 20 fixed to one end of a horizontal shaft 21 which is rotatably mounted in the vertical arm of bearing 18 and a bearing 22. A plurality of ratchet wheels 23, 24, 25 in side by side relation, are fixed to an intermediate portion of shaft 21 and are arranged so that their respective teeth are in staggered relation. The ratchet wheels are respectively engaged by pawls 26, 27, 28 mounted on a stud 29 which is fixed to the upper end of an arm 30 having a fulcrum portion freely swingable on shaft 21.

The lower portion 31 of arm 30 is formed with an elongated, rectangular shaped slot 32 which receives a slide block 33. The arm 30 is oscillated about shaft 21, through a linkage including a link 34 which is pivoted at one end on a stud 33a extending from block 33 and is pivotally connected at the other end thereof to a stud 35a extending from a slide block 35 slidably received in a rectangular slot 36 formed in an oscillatory arm 37.

The arm 37 is actuated by means of a constant speed drive shaft, such as the main cam shaft 38 of the knitting machine of which the beam drive is a part. A cam 39 on shaft 38 engages a follower 40 mounted on the upper end of arm 37 which is mounted for oscillation on a stud 37a extending from the knitting machine frame, not shown. The cam 39 is suitably shaped to impart the desired oscillatory movement to arm 37 and a spring 41 secured at one end to the upper end of the arm and suitably anchored at the other end, keeps the follower 40 in engagement with the cam.

It will be apparent that the rotary motion of shaft 38 is translated into oscillatory motion by means of the

arms 37, 30 and connecting link 34, thereby actuating the pawls 26, 27, 28, which in turn rotate the ratchet wheels 23, 24, 25 so as to drive shaft 15. With the staggered arrangement of the ratchet wheels, the time intervals between the throw of the pawls are so small as to make the intermittent actuation of the drive shaft almost continuous.

Means is provided for regulating the operation of the drive shaft actuating means so as to vary the let off of the threads or yarn from the beam and thereby determine the quality characteristics of the knitted fabric. To this end, the position of the slide block 35 in slot 36 may be adjusted by means of a screw 42 whose lower portion engages a vertically threaded portion of the block. A bevel gear 43 is fixed to the upper end of screw 42 and engages a bevel gear 44 fixed to a horizontal stud shaft 44a journaled in the arm 37. A handle 45 on the stud shaft 44a permits micrometer adjustment of the slide block 35 and thereby regulates the throw of the pawls through link 34 and slide block 33 on arm 30.

Means is also provided for adjusting the feed of the beam let off as the diameter of the beam decreases with continued supply of thread to the knitting instrumentalities. This is accomplished automatically by means of a horizontally disposed roller 46 mounted on the upper end of an arm 47 of a bell crank 48 fulcrumed at 49. The roller 46 is urged into contact with the periphery of the beam by a spring 50 attached to the crank arm 47 and anchored to the machine frame. The other crank arm 51 is pivotally connected to the upper end of a vertical link 52, the lower end of which is pivotally connected to slide block 33.

It will be apparent that as the beam diameter decreases, as from A to B, roller 46 will move toward the beam shaft 13, causing crank 48 to pivot in a counterclockwise direction. This will lift the slide block 33 upwardly in arm slot 32, through link 52. The position of the arm 30 will be changed relative to shaft 21, due to the change in position of the block 33 as from a point x measured from the axis of shaft 21 to a point y also measured from the same axis. This will produce a proportionate change in the stroke of the pawls so as to increase the rotational speed of the beam shaft and thereby maintain the linear speed of the beam let off substantially constant. The arm 30 should be formed so that the ratio of the distances x to y is about the same as the ratio of the maximum beam diameter A to the minimum beam diameter B.

When knitting fabrics of the type which have blind or floating stitches, the feed of thread or yarns from the beam must be suspended for a predetermined number of knitting cycles. Accordingly, there is provided means for rendering the beam feed inoperative for intervals determined by the stitch construction of the desired fabric. To this end, a curved sheet of metal 53 is positioned over the teeth of the ratchet wheels by means of an arm 54 of bell crank 55 which is pivotally mounted on shaft 21.

The other arm 56 of bell crank 55 is pivotally connected to a link 57 which is connected to the armature 58 of a solenoid 59. The winding on the solenoid is connected to a suitable source of current indicated at terminals 60, through a micro switch 61. The switch arm 62 is actuated to its closed position by cam means in the form of short, arcuate strips 63 mounted on a pattern wheel 64 which forms a part of the knitting machine. The cam strips 63 are positioned on wheel 64 so as to correspond to the knitting cycles during which the feed of threads from the beam is to be suspended.

Upon closing the switch 61, through the cam strips, the solenoid winding is energized, thereby moving the bell crank in a clockwise direction. The curved metal sheet 53 will be moved to an angular position wherein the teeth of the ratchet wheels will be shielded against engagement by the pawls. Accordingly the actuation of

the pawls will be ineffective to drive shaft 15 and the beam 11 will cease to rotate until such time as the microswitch 61 is opened when the armature 58 will be retracted by spring means not shown. The bell crank 55 will be pivoted in a counterclockwise direction to move the shield 53 to a position where it will no longer interfere with the engagement of the ratchet wheels by the pawls and the drive of the beam will be resumed.

It is understood that the switch arm 62 may be actuated by any suitable cam means related to the knitting cycles of the machine, such as pattern chains or the like.

It will thus be seen that there has been provided a beam drive in which the several objects of the invention have been achieved and which is well adapted to meet the conditions of practical use.

As various possible embodiments might be made of the invention described, and as various changes might be made in the embodiment set forth herein, it is understood that all matter herein shown or described, is to be interpreted as illustrative and not in a limiting sense.

Having thus described my invention, I claim as new and desire to protect by Letters Patent:

25 1. In a knitting machine, a beam, means for positively rotating said beam, means for suspending the operation of said beam rotating means for a predetermined number of knitting cycles, and means for automatically actuating said suspending means at predetermined intervals during the operation of the machine.

2. In a knitting machine, a beam, a drive shaft for rotating said beam, a power shaft, pawl and ratchet means connecting said power and drive shafts for imparting intermittent angular movement to said drive shaft and means for automatically rendering said pawl and ratchet means inoperative at predetermined intervals during the operation of the machine.

3. In a machine as in claim 2 and further including a shield located over the teeth of the ratchet and arranged for angular movement towards and away from a position rendering the pawl inoperative, and means for moving said shield.

4. In a machine as in claim 2, and further including means responsive to changes in the beam diameter for regulating the operation of said pawl and ratchet arrangement.

5. In a knitting machine, a beam drive comprising a drive shaft, a power shaft and clutch means connecting said shafts comprising a pair of oscillatable arms, one of said arms being arranged for oscillation by said power shaft and being formed with a slot, ratchet means for rotating said drive shaft, pawl means on the other of said arms for actuating said ratchet means, said other arm being formed with a slot, a block slidably mounted in the slot of each of said arms, a link pivotally connecting said blocks and micrometer means for adjusting the position of the block in the slot of said one arm.

6. In a machine as in claim 5, and further including a roller adapted to bear against the periphery of the beam, a bell crank for supporting said roller, and a link pivotally connecting said bell crank and the block on said other arm.

7. In a machine as in claim 5, and further including a shield located over the teeth of said ratchet means and angularly movable towards and away from a position between said pawl means and the teeth of said ratchet means, solenoid means for actuating said shield, a circuit including said solenoid means and switch means, and cam means for actuating said switch means.

8. In a knitting machine, a beam, a drive shaft for rotating said beam, a power shaft, means connecting said shafts comprising a pair of oscillatory arms, a link connecting said arms and movably mounted thereon, driving means connecting said drive shaft and one of said arms, means for adjusting the position of said link

5

relative to the other of said arms, and means for adjusting said link relative to said one arm in response to changes in beam diameter.
